US00D625303S

(12) **United States Design Patent**
Kim

(10) **Patent No.:** **US D625,303 S**
(45) **Date of Patent:** **** Oct. 12, 2010**

(54) **MOBILE PHONE CASE**

(76) Inventor: **Dae-Young Kim**, 1-509 Seongyeong Apt. 506 Daechi-dong, Gangnam-gu, Seoul (KR)

(**) Term: **14 Years**

(21) Appl. No.: **29/326,303**

(22) Filed: **Oct. 15, 2008**

(30) **Foreign Application Priority Data**

Aug. 19, 2008 (KR) 30-2008-0035912

(51) **LOC (9) Cl.** **14-03**

(52) **U.S. Cl.** **D14/250**

(58) **Field of Classification Search** D14/140, D14/142, 167, 217, 218, 240, 242, 248, 250–253, D14/299, 341–347, 440; D3/200–201, 215, D3/218–219, 226, 228, 269, 301, 272–273, D3/276, 294; D13/103, 107–108, 119; 220/4.02; 224/191, 240, 241, 245, 682–683; 248/206.2–206.4, 248/220.21, 279.1, 309.1; 361/679.3, 679.56; 379/420.04, 433.11; 455/575.8, 575.9; 190/100; 206/305, 320

See application file for complete search history.
